BEVERAGE VENDING MACHINE

Khoren C. Melikian and Lloyd K. Rudd, Philadelphia, Pa.

Application June 18, 1948, Serial No. 147,056

Term of patent 14 years

(Cl. D2—3)

To all whom it may concern:

Be it known that we, Khoren C. Melikian and Lloyd K. Rudd, citizens of the United States, residing at Philadelphia, State of Pennsylvania, have invented a new, original, and ornamental Design for a Beverage Vending Machine, of which the following is a specification, reference being had to the accompanying drawing, forming part thereof.

In the drawing:

Fig. 1 is a perspective view of a beverage vending machine showing our new design, the broken line portion suggesting the manner of supporting the machine for illustrative purposes only.

Fig. 2 is a side view thereof; and

Fig. 3 is a plan view.

The side of the beverage dispensing machine not disclosed is identical in appearance as the side shown. The rear is plain.

We claim:

The ornamental design for a beverage vending machine, as shown and described.
